UNITED STATES PATENT OFFICE.

JOHN W. GURLEY, OF INDIANAPOLIS, INDIANA, ASSIGNOR TO MURDOCK PUMP COMPANY, OF INDIANAPOLIS, INDIANA, A CORPORATION OF INDIANA.

PUMP.

Application filed July 14, 1924. Serial No. 725,859.

It is the object of my invention to improve the operation of and to reduce friction between the moving parts of rotary pumps and fluid-pressure motors of the type in which a rotary element is provided with a series of retractible blades, such rotary element rotating within a casing, the interior of which is so shaped that the spaces between the blades are alternately expanded and contracted as the rotatable element is rotated.

A pump or fluid-pressure motor of this type is shown in my Patent No. 1,472,414, granted October 30, 1923; and the present invention consists of a modification of the type of pump shown in this patent, by which modification the operation of the pump is bettered and the wear of moving parts materially reduced.

I accomplish the objects above set forth by providing a cylindrical metal shell which is concentric with the interior of the pump-casing, which lies between the casing and the rotor, and which rotates with the same average angular velocity as does the rotor.

The accompanying drawings illustrate my invention: Fig. 1 is a longitudinal central section of a pump embodying my invention; Fig. 2 is a cross section of such pump on the line 2—2 of Fig. 1; Fig. 3 is a cross section on the line 3—3 of Fig. 1; Fig. 4 is a horizontal longitudinal section on the line 4—4 of Fig. 2; Fig. 5 is a perspective view, in partial section, of the rotor and shell removed from the casing showing one of the shell-hubs removed from the shell; and Figs. 6 to 10 inclusive are perspective views of the casing end-plate, one of the rods which limit the extent of relative rotation between the rotor and shell, a blade-shoe, a blade, and the shell respectively.

The pump has a casing 10, provided with a central cylindrical bore, and two end plates 11. The end plates contain bearings for a shaft 12 which passes through the cylindrical bore of the casing 10 parallel to but displaced from the axis of such cylindrical bore. Rigidly mounted on this shaft 12 is the rotor 13 which is provided with a plurality of pairs of retractible blades 14, preferably equally spaced around the circumference of the rotor and radially slid-able in grooves in such rotor. Preferably, each pair of blades are connected together

by one or more pins 15 which extend through the rotor and are radially slidable therein so that when one blade of a pair is forced inward of the rotor the opposite blade will be positively forced outward.

Rotatably mounted within the cylindrical bore of the casing 10 is a thin walled cylindrical shell 16, concentric with such bore and supported by means of two shell-hubs, pressed in the opposite ends thereof for securing said shell and hubs together, each of which is provided with a projecting flange 18 which enters a suitable bearing recess in an end plate 11, as is clear from Fig. 1. The flange 18 may be either integral with the shell-hub 17 or may be merely the extending end of a bushing pressed into the bore of such shell-hub. The exterior diameter of the shell 16 is very slightly less than the diameter of the cylindrical bore of the casing 10. For reasons which will later appear, the shell 16 is provided with groups of longitudinally extending slots 16', the number of such groups being equal to the number of blades in the rotor 13, and the shell 16 being so angularly located relative to the rotor 13 that each group of slots 16' is substantially midway between two blades.

As the axis of rotor-rotation is eccentric to the cylindrical bore of the casing 10, I prefer to provide on the outer edge of each blade 14 a rocking shoe 20, the exterior surface of which is a portion of a cylindrical surface of a diameter equal to the internal diameter of the shell 16. The inner surface of each shoe 20 is a convex cylindrical surface resting in a correspondingly curved groove in the outer edge of its blade 14. As the rotor 13 and shell 16 rotate within the casing 10, the shoes 20 rock in the grooves of the blades 14 so that the outer surfaces of such shoes are always in contact with the inner surface of the shell 16. As the rotor rotates, the distance between opposite shoes 20 will vary. This variation is slight—too slight to be shown in the drawings—and it is taken care of by relative movement between the shoes and their respective blades in the manner described in my prior Patent No. 1,472,414, mentioned above.

The outer surface of each shoe 20 is provided with a longitudinal groove in which is fixed a bar 21 which is longer than the shoe and which projects longitudinally be-

yond each end thereof. The exterior surface of each bar 12 is finished to conform to the exterior surface of its shoe 20. The projecting ends of the bars 21 extend into slots 22 formed in the periphery of the shell-hub 17, which slots are of sufficient circumferential extent to permit a limited relative movement of the rotor and shell. This relative movement of rotor and shell is necessary, because the shell, which is driven from the rotor 13 and is eccentric relative thereto, will not have at all points in its revolution the same angular velocity as does the rotor, although the average velocity of shell and rotor will be the same. The different positions which the projecting ends of the bars 21 assume in the slots 22 as the rotor rotates is shown clearly in Fig. 2.

The casing 10 is provided with an inlet opening 25 and a discharge opening 26, which openings communicate respectively with passages 27 and 28 extending longitudinally of the casing. The passages 27 and 28 communicate with depressions 29 in the end-plates 11, and these depressions 29 serve to connect the passages 27 and 28 with the interior of the shell 16.

It will be evident that as the rotor 13 and shell 16 rotate within the casing 10, the four compartments into which the space between the rotor and shell is divided by the blades 14 will alternately increase and decrease in size. The depressions 29 in the plates 11 are so shaped that as the rotor rotates in a clockwise direction (Fig. 3) the two spaces which are increasing in size will communicate with the fluid-passage 27 and the two spaces which are decreasing in size will both communicate with the fluid passage 28. As each space increases in size, fluid is drawn in through the passage 27 to

fill such space and when this space so filled begins to decrease in size, the fluid contained within it will be positively forced into the passage 28 and out through the discharge opening 26. Either opening 25 or 26 can serve as the inlet opening, and the other as the discharge opening, depending on the direction of rotor rotation.

As the shoes 20 do not engage the interior of the stationary casing 10 but engage the interior surface of the rotating shell 16, there is but little wear on the exterior surfaces of these shoes. The openings or slots 16' serve to balance the pressure within and without the shell 16 so that there is no tendency to distort such shell.

While I have described my device as a pump, it is capable of efficient use, without change, as a rotary fluid-pressure motor; and my claim is intended to cover the device regardless of the use to which it may be put.

I claim as my invention:—

A rotary pump, comprising a casing having a cylindrical chamber, a hollow cylindrical shell rotatably mounted within said chamber, said shell and chamber being co-axial, a rotor rotatable within said shell on an axis eccentric to said chamber, a hub at each end of said shell for supporting the same, a plurality of slots formed adjacent the periphery of each of said hubs, and bars mounted in said rotor having their ends extending into said slots and slidably therein for providing a lost motion driving connection therebetween, whereby said co-axial shell may be driven by said eccentric rotor.

In witness whereof, I have hereunto set my hand at Indianapolis, Indiana, this 10th day of July, A. D. one thousand nine hundred and twenty-four.

JOHN W. GURLEY.
